UNITED STATES PATENT OFFICE.

MONROE V. W. DE MOTT, OF NEW YORK, N. Y.

DESIGN FOR A CAKE OF SOAP.

54,390.

Specification for Design.

Patented Feb. 10, 1920.

Application filed April 4, 1919. Serial No. 287,625. Term of patent 14 years.

To all whom it may concern:

Be it known that I, MONROE V. W. DE MOTT, a citizen of the United States, residing in New York, county of New York, and State of New York, have invented a new, original, and ornamental Design for a Cake of Soap, of which the following is a specification, reference being had to the accompanying drawing, forming part hereof.

In the drawings—

Figure 1 is a plan view of a cake of soap showing my new design;

Fig. 2 is a view of the same in side elevation; and

Fig. 3 is a view of the same in end elevation.

I claim:

The ornamental design for a cake of soap, as shown.

MONROE V. W. DE MOTT.
